Primary Examiner — Michelle E. Wilson*Assistant Examiner* — Clese Moore, Jr.*(74) Attorney, Agent, or Firm* — Michael J Porco; Gerald E Hesplos(57) **CLAIM**

The ornamental design for a swaddle transition bag, as shown and described.

DESCRIPTION

FIG. 1 is a perspective view of a swaddle transition bag showing my new design;

FIG. 2 is a front view thereof;

FIG. 3 is a rear view thereof; and,

FIG. 4 is another perspective view thereof, showing the saddle transition bag in a usage state.

The dashed stitch lines and the broken lines depict portions of the swaddle transition bag that form no part of the claimed design.
